UNITED STATES PATENT OFFICE.

JOSEPH M. FEINSON, OF NEW YORK, N. Y.

NECKWEAR.

Application filed February 4, 1927. Serial No. 165,784.

My present invention is concerned with neckwear and more especially with four-in-hand neckties.

It is an object of the invention to provide a neck tie which can be readily slipped, preparatory to tying, between the neckband and the flap of a turnover collar, without undue strain on the necktie, and which will not crumple or become disfigured even after prolonged use.

As conducive to a clear understanding of the invention, it may be noted, that the usual linings of neck ties, if loosely disposed, are likely to shift and to crumple and thereby disfigure the tie after a period of use. If such linings are tightly stitched in place, the neckband of the tie is rendered non-resilient and it therefore slips with difficulty, in a turndown collar and with possible injury to the tie.

Hence, it is another object to avoid the use of a lining filler or stuffing within the tie and to accomplish the advantages recognized as inherent in well-made single ply ties, while economizing in the quantity of the expensive fabric used for such ties, and at the same time avoiding the raw and unfinished appearance of the inner face of such ties.

According to the invention the neck tie is formed of two plies without an enclosed lining, an outer ply of the usual neck tie material and an inner ply of less expensive fabric. The plies are stitched together completely about their raw edges except at the neck band forming part. The ends of the stitched plies are then turned inside out to conceal the raw edges and the stitching within the interior of the tie. Sufficient fabric is used to form preferably a quadruple layer of the double ply material, that is eight layers of fabric at one end of the tie and six such layers at the narrower end of the tie. The neck band forming part is folded together to conceal the raw edge and loose stitching, preferably a single line thereof, holds the same together.

In the accompanying drawings in which is shown one of the various possible embodi-

ments of the several features of the invention,

Fig. 1 is a plan view of the superposed blanks,

Fig. 2 is a similar view showing the blanks stitched together,

Fig. 3 is a sectional view taken on line 3-3 of Fig. 2,

Fig. 4 is a figure similar to Fig. 2, showing the ends of the blanks turned inside out,

Fig. 5 is a sectional view taken on line 5-5 of Fig. 4,

Fig. 6 is a plan view showing the tie preparatory to being folded together, and

Fig. 7 is an inner view of the completed tie.

The necktie blank (Fig. 1) forming the outer ply, which for economy of material, may be formed of two lengths, 10 and 11 stitched together along diagonal line 12, has the usual blunted narrower end 13. At the opposite end this blank has a wider wing 14 which preferably represents an integral rectangular extension beyond the diagonal line *a*—a limiting the otherwise generally triangular conformation of the main blank. An inner ply 15 of size and shape preferably identical with the outer ply but of less expensive material is shown underneath in Fig. 1. This inner ply also may be formed of two segments 15 and 16, preferably stitched together along a diagonal line 20, preferably intersecting the diagonal line 12 of the other or outer superposed ply 10—11. The two plies are stitched together completely about their ends as at 17 and 18 and along their sides, leaving the edges of the intermediate neck band forming portion 19 completely unattached. The hand may readily be passed through the opening between the two plies of the intermediate part 19, and the opposite closed bag ends turned inside out so that the raw edge is turned inwardly as appears best from Figs. 4 and 5, so that the seams or stitches 17 and 18 will now be concealed between the plies of the tie as will also the raw edges of the plies, affording a finished edge or seam 17', and 18'.

To complete the tie, the material is

creased along a slightly curved line 21 (Fig. 6) which extends longitudinally of the tie from the oblique edge 23 of one end, and terminates at 25 at the lateral edge near the opposite end. The fold 26 thus formed, has a corner 27 folded back along crease 28 so as not to overlap the longitudinal slightly curved crease 29 extending from end to end of the tie. An intermediate strip or fold 10 41 longitudinally of the tie, is thus bounded by creases 29 and 21. A crease 30 extends along a curve the entire length of the tie, forming a corresponding fold 31. The creases 29 and 30 determine the lateral edges 15 of the main panel 40 of the completed tie shown in Fig. 7.

It will be noted that three superposed layers are provided at the narrower end shown near the upper edge of the drawings 20 comprising the main or central panel 40, the upper end of fold 31 and the upper end of fold 41. At the opposite end of the tie, the material is in four layers, as appears clearly from Figs. 6 and 7 comprising the main or 25 central panel 40, the corresponding end of fold 31 at the right edge, and the two superposed folds 41 and 26 at the left edge.

By the folding set forth the raw unstitched edges at the intermediate part of the 30 correlated blanks are brought to the interior of the tie and concealed therein. Loose stitching, preferably a single line thereof 47, maintains the neck band in assembled relation. The loose stitch is knotted at its 35 ends 47' in manner well understood, to afford slack or lost motion for extension of the tie, without stress upon or resistance by the thread.

Where a two ply neck tie is formed of a 40 blank not much greater in width than that of the finished tie, an intermediate filler or liner member is ordinarily required. Where the two plies are stitched together completely about their raw edges, a double 45 seam or welt will be formed within the length of the neck band, in addition to the line of stitching to retain the neck band in folded condition. Such construction is not only more expensive to produce than that 50 of my invention, but the double welt adds to the thickness if not to the rigidity of the neckband, thereby preventing proper slipping of the neckband at the collar.

Considering the fact that my tie is double 55 ply, six layers of material are provided at the narrower or triple folded end and eight layers at the wider or quadruple folded end. In a single ply tie, much more of the expensive outer fabric is required than by me, 60 since ordinarily the material in such tie is folded to afford no less than seven superposed layers at the wider end.

It will thus be seen that there is herein described an article in which the several features of this invention are embodied, and

which in service attains the various objects of the invention and is well suited to meet the requirements of practical use.

As many changes could be made in the above construction, and many apparently 70 widely different embodiments of this invention could be made without departing from the scope thereof, it is intended that all matter contained in the above description or shown in the accompanying drawings shall 75 be interpreted as illustrative and not in a limiting sense.

Having thus described my invention, what I claim as new and desire to secure by Letters Patent is:

1. A neck tie comprising a pair of plies of substantially identical dimensions having the borders thereof stitched together adjacent their ends only and having a neck band portion between said stitched parts, the 85 said neck band portion being held together in finished folded state by loose stitching.

2. A neck tie comprising a pair of superposed plies of substantially identical dimensions, one forming the exterior and the other 90 the interior of the tie, the borders of said plies stitched together adjacent their ends only and having a neck band portion between said stitched parts, said latter part being held in assembled position by loose 95 stitching.

3. A neck tie comprising a pair of plies of substantially identical dimensions, one forming the exterior and the other the interior of a double ply tie, said plies stitched together at the borders thereof adjacent their ends only and from beyond the intermediate or neckband part thereof to each end, the ends thereof being turned inwardly to conceal the raw edges within the interior thereof, the intermediate part thereof being folded and stitched together to form a neck band. 105

4. A neck tie comprising a pair of superposed blanks of substantially identical dimensions, the borders of said blanks stitched together adjacent their ends only, said neck tie having a neck band portion between said stitched parts, the correlated blanks being folded the entire length thereof near one longitudinal edge thereof, and being folded near 110 the other longitudinal edge thereof along a line extending from one end to the lateral edge near the opposite end thereof, whereby the completed tie will have a triple layer of the correlated fabrics at said latter end and a 115 quadruple layer at the opposite end, said neckband portion being held together in finished folded state by loose stitching.

5. A neck tie comprising a pair of superposed blanks of substantially identical dimensions having their borders stitched together adjacent their ends only and having a neck band portion between said stitched parts, the ends of said correlated blanks being turned inwardly to conceal the raw edges 120 125 130

within the interior thereof, the correlated blanks being folded the entire length thereof near one longitudinal edge thereof and being folded near the other longitudinal edge 5 thereof along a line extending from one end to the lateral edge near the opposite end thereof, whereby the completed tie will have a triple layer of the correlated fabrics at

said latter end and a quadruple layer at the opposite end; the neck band forming part 10 being held together by loose stitching.

Signed at New York in the county of New York and State of New York this 1 day of February A. D. 1927.

JOSEPH M. FEINSON.
